United States Patent

Des. 238,330

Patented Jan. 6, 1976

238,330

HANDLE FOR A TRAY OR THE LIKE

Manuel S. Ziskin, Mayfield Heights, and Harold O. Wagner, Sheffield Lake, Ohio, assignors to American Trading & Production Corporation, Baltimore, Md.

Filed July 11, 1974, Ser. No. 487,601

Term of patent 14 years

Int. Cl. D8—06

U.S. Cl. D7—39

Fig. 1

Fig. 2

Fig. 3

Fig. 4

FIG. 1 is a top plan view of a handle for a tray or the like showing our new design;

FIG. 2 is a front elevational view;

FIG. 3 is a bottom plan view; and

FIG. 4 is a side elevational view thereof.

In rear elevation the grip portion is identical in configuration to that shown in FIG. 2 and the surface of the bracket is flat and unornamented.

We claim:

The ornamental design for a handle for a tray or the like, substantially as shown and described.
